INVENTOR

Olive Seacord

UNITED STATES PATENT OFFICE.

OLIVE SEACORD, OF WASHINGTON, DISTRICT OF COLUMBIA.

DESIGN FOR SHOE-PASTE APPLIER AND POLISHER.

56,835.

Specification for Design.

Patented Dec. 28, 1920.

Application filed February 10, 1920. Serial No. 357,687. Term of patent 7 years.

To all whom it may concern:

Be it known that I, OLIVE SEACORD, a citizen of the United States, residing at 1836 Connecticut avenue, Washington, D. C., have invented a new and original Design for a Shoe-Paste Applier and Polisher, of which the following is a specification, reference being made to the accompanying drawing, forming a part thereof in which the figure shown is a perspective view showing my new design. The projecting mem-

ber or dauber and the main body or polisher are both covered with cloth that can be renewed when soiled or worn. The rounded portion of the polisher is especially fitted to the surface of the shoe, with the pointed end for edges.

I claim:

An ornamental design for a shoe paste applier and polisher as shown and described.

OLIVE SEACORD.
